UNITED STATES PATENT OFFICE.

LEONARD J. HILL, OF GRAND RAPIDS, MICHIGAN.

EXTENSION TABLE.

Application filed February 9, 1925. Serial No. 7,970.

This invention relates to improvements in extension tables.

My improved extension table is especially designed by me for use as a combined library or like table and dining table, although of course its use is not limited.

The main object of the invention is to provide an improved extension table which may be easily extended or collapsed and which is attractive in appearance, both when collapsed and extended.

A further object is to provide a table having these advantages which is economical in structure and at the same time strong and rigid.

Objects pertaining to details and economies of my invention will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a transverse section of my improved table in collapsed adjustment, the legs being partially broken away.

Fig. II is a longitudinal section on a line corresponding to line 2—2 of Fig. I.

Fig. III is a fragmentary plan view with the table extended.

Fig. IV is a detail transverse section on a line corresponding to line 4—4 of Fig. III.

Fig. V is a detail section on a line corresponding to line 5—5 of Fig. II.

In the drawing the sectional views are taken looking in the direction of the little arrows at the ends of the section lines and similar numerals of reference indicate similar parts in all of the views.

Referring to the drawing, I provide a bed which in the structure illustrated comprises side rails or members 1 and end members 2 connected to the legs 3. A top member 4 is fixed to this bed. I also provide a pair of adjustable top members 5 which are adapted to be telescoped over the fixed top member or to be adjusted into the plane thereof as shown in Fig. IV constituting extensions of the fixed top member.

To the under sides of adjustable top members 5 I secure supplemental top members 6, their outer edges being flush with the outer edges of the top members 5. The supple-

mental top members are adapted to complement the top member 4 and to rest upon the side rails 1 of the bed when the table is collapsed. The adjustable top members 5 and these supplemental top members 6 are carried by slides 7, the outer ends of the slides being secured to the under sides of the supplemental top members 6 as illustrated.

These slides 7 are adapted to slide through the openings 8 in the side rails 1 and are supported by the bottoms of the slots. The slides are arranged in opposed pairs, that is, side by side as shown in Fig. II, and between the slideways 9. These slideways have inwardly inclined grooves 10 on their inner faces which are engaged by the latterly projecting pins 11 on the slides. These grooves are in effect cam grooves for controlling the position of the adjustable top members as they are moved to and from extended position.

The slides have notch-like recesses 12 in their bottom edges adapted to receive the bed members 1 when the slides are extended permitting the adjustable top members to drop down into the plane of the fixed top member. The cam grooves 10 in the slideways have hook-like outer portions 13 in which the pins travel when the notches are in register with the rails 1 thereby permitting the slides to drop down and also to have a limited longitudinal movement when in this lowered position, the notches being of such length as to permit this movement. This allows the adjustable top members to be dropped down into the plane of the top and slide horizontally to engage the dowels 14 as illustrated in Fig. IV. The fully extended position of the slide is indicated by dotted lines at the left of Fig. IV.

The slides also have outwardly inclined cammed edges 15 which coact with the wedge-shaped cams 16 on the under side of the fixed table top to permit the tilting of the slides and to support the inner ends of the slides when the table is extended.

When it is desired to extend the table the adjustable sections are drawn out as far as possible which brings the notches 12 into register with the bed members which permits the adjustable top sections to drop down into the plane of the fixed top section. The adjustable top section is then pushed in to the position shown in Fig. IV in which the top sections are brought edge to edge with their coacting dowels in engagement.

To collapse the table, the adjustable sections are again pulled out to the limit of their outer movement and lifted up, the movement being guided by the pins 11 traveling in the hooked portions of the grooves 10 and the sections pushed in as indicated by dotted lines in Fig. IV until the adjustable sections are brought edge to edge, in which position they lie horizontally.

- 10 With the supplemental sections edge to edge with the fixed top section as shown in Fig. I, my improved table is especially designed as a combined library or like table and dining table. It has the advantage of 15 being attractive in appearance, very rigid either when collapsed or extended, and may be easily manipulated. When the table is collapsed it shows but one line of opening and when extended but two lines of opening.
- 20 I have illustrated and described my improvements in a simple and practical embodiment thereof. I have not attempted to illustrate or describe certain modifications or adaptations which I contemplate as I believe 25 the disclosure made will enable those skilled in the art to embody or adapt the same as may be desired.

Having thus described my invention what I claim as new and desire to secure by Letters 30 Patent is:

1. In an extension table, the combination of a bed comprising members having slide openings therein, a relatively fixed top member, a pair of adjustable top members adapted 35 to telescope over said fixed top member or when extended to constitute extensions therefor, supplemental members secured to the under sides of said adjustable top members with their outer edges flush with the outer 40 edges thereof and adapted to complement said fixed top member when the adjustable top members are telescoped over the same, slides upon which said supplemental and adjustable top members are mounted arranged through 45 said slide openings in said bed in oppositely disposed pairs and having notches in their under edges permitting the adjustable top members to drop to the plane of the fixed top member when the slides are extended, the 50 upper edges of the inner portions of said slides being outwardly inclined, cams on the under side of said fixed top member coacting with said inclined edges of said slides, slideways disposed at the sides of the pairs of slides 55 and having inwardly inclined grooves on their inner faces terminating at their outer ends in downwardly disposed hook-like portions, and laterally projecting pins on said slides coacting with said grooves, said pins being 60 disposed adjacent the notches of the slides, the notches of the slides being of such length as to permit longitudinal adjustment of the slides while the notches are engaged with the bed members.

- 65 2. In an extension table, the combination

of a bed comprising members having slide openings therein, a relatively fixed top member, a pair of adjustable top members adapted to telescope over said fixed top member or when extended to constitute extensions therefor, slides upon which said adjustable top members are mounted arranged through said slide openings in said bed in oppositely disposed pairs and having notches in their under edges permitting the adjustable top members to drop to the plane of the fixed top member when the slides are extended, the upper edges of the inner portions of said slides being outwardly inclined, cams on the under side of said fixed top member coacting with said inclined edges of said slides, slideways disposed at the sides of the pairs of slides and having inwardly inclined grooves on their inner faces terminating at their outer ends in downwardly disposed hook-like portions, and laterally projecting pins on said slides coacting with said grooves, said pins being disposed adjacent the notches of the slides, the notches of the slides being of such length as to permit longitudinal adjustment of the slides while the notches are engaged with the bed members.

3. In an extension table, the combination of a bed comprising members having slide openings therein, a relatively fixed top member, a pair of adjustable top members adapted to telescope over said fixed top member or when extended to constitute extensions therefor, supplemental members secured to the under sides of said adjustable top members with their outer edges flush with the outer edges thereof and adapted to complement said fixed top member when the adjustable top members are telescoped over the same, slides upon which said supplemental and adjustable top members are mounted arranged through said slide openings in said bed in oppositely disposed pairs and having notches in their under edges permitting the adjustable top members to drop to the plane of the fixed top member when the slides are extended, the upper edges of the inner portions of said slides being outwardly inclined, cams on the under side of said top member coacting with said inclined edges of said slides, slideways having cam grooves therein, and pins on said slides coacting with said grooves, the notches of the slides being of such length as to permit longitudinal adjustment of the slides while the notches are engaged with the bed members.

4. In an extension table, the combination of a bed comprising members having slide openings therein, a relatively fixed top member, a pair of adjustable top members adapted to telescope over said fixed top member or when extended to constitute extensions therefor, slides upon which said adjustable top members are mounted arranged through said slide openings in said bed in oppositely dis-

posed pairs and having notches in their under edges permitting the adjustable top members to drop to the plane of the fixed top member when the slides are extended, the upper 5 edges of the inner portions of said slides being outwardly inclined, cams on the under side of said top member coacting with said inclined edges of said slides, slideways having cam grooves therein, and pins on said 10 slides coacting with said grooves, the notches of the slides being of such length as to permit longitudinal adjustment of the slides while the notches are engaged with the bed members.

15 5. In an extension table, the combination of a bed comprising members having slide openings therein, a relatively fixed top member, a pair of adjustable top members adapted to telescope over said fixed top member 20 or when extended to constitute extensions therefor, supplemental top members secured

to the under sides of said adjustable top members and adapted to complement said fixed top member when the adjustable top members are collapsed over the same to collapse the table, cammed slides upon which 25 said supplemental and adjustable top members are mounted arranged through said slide openings in said bed and having recesses in their under edges permitting the adjustable 30 top members to drop to the plane of the fixed top member when the slides are extended, there being members on said fixed member coacting with the cams of said slides, and slideways having cam grooves therein operatively associated with said slides, said 35 slides being provided with pins coacting with said grooves, for the purpose specified.

In witness whereof I have hereunto set my hand.

LEONARD J. HILL.
